 Bodner & O'Rourke, LLP

(57) **CLAIM**

The ornamental design for headlight for a motor vehicle grille, as shown and described.

DESCRIPTION

FIG. 1 shows a front view of the lights;
 FIG. 2 shows a rear view of the lights;
 FIG. 3 is a top view of the lights;
 FIG. 4 is a bottom view of the lights;
 FIG. 5 is a first end view of the lights;
 FIG. 6 is a second end view of the lights; and,
 FIG. 7 shows the lights of FIG. 1 embedded in a vehicle grille, which is shown with broken lines, it being understood that the broken lines are for illustrative purposes only and form no part of the claimed design.

1 Claim, 7 Drawing Sheets
